Philip T. Dodge

UNITED STATES PATENT OFFICE.

AMASA C. KASSON, OF MILWAUKEE, WISCONSIN.

DESIGN FOR A KNIFE-SHARPENER.

SPECIFICATION forming part of Design No. 14,803, dated September 18, 1883.

Application filed March 22, 1883. Term of patent 7 years.

To all whom it may concern:

Be it known that I, A. C. KASSON, of Milwaukee, in the county of Milwaukee and State of Wisconsin, have invented certain Improvements in Designs for Knife-Sharpener, of which the following is a specification.

This invention relates to an improved form or configuration for that class of knife-sharpening devices which consist of a body or stock 10 coated with or composed of emery or equivalent material.

Referring to the accompanying drawings, Figure 1 is a perspective view representing my improved device. Fig. 2 is a perspective view, 15 looking against the outer end.

A represents the body portion of the design, or portion which will be coated with emery. It is made, as shown, of a circular or substantially circular form in cross-section, 20 and tapered or diminished in diameter from the two ends toward the middle, this characteristic constituting the important feature of the design. The body portion is preferably extended endwise beyond the emery-surface α , 25 as shown at b , these annular projecting portions or extensions being made of greater diameter than the adjacent surface, as clearly shown in Fig. 1. At one end the body is provided with a central elongation or handle, B;

in the form represented, this feature, however, 30 being of secondary importance. At that end of the body opposite the handle a cushion or block of emery or equivalent material, D, projects outward beyond the end of the body, as shown.

As before stated, the leading feature of the design consists in the body portion having the round or circular section of diminishing size from its two ends toward the center.

The present invention is restricted to those 40 matters and things which are hereinafter claimed, and as to all matters which may be described or shown, but which are not claimed, the right is reserved to make the same the subject of a separate application.

Having thus described my invention, what I 45 claim is—

1. The design for a knife-sharpener, substantially as herein described and shown.
2. In a design for a knife-sharpener, the body 50 portion of round section and diminishing diameter toward its center, combined with the projecting end portion, D.

AMASA C. KASSON.
